(57) **CLAIM**

We claim the ornamental design for a bottle portion, as shown and described.

DESCRIPTION

FIG. 1 is a perspective view of a bottle portion embodying our new design; FIG. 2 is a front elevational view of the bottle portion depicted in FIG. 1;

FIG. 3 is a side view of the bottle portion depicted in FIG. 2, representing a partial rotation of the bottle portion about its vertical center axis from the front elevational view depicted in FIG. 2, the opposite side elevational view being a mirror image thereof;

FIG. 4 is a rear elevational view of the bottle portion depicted FIG. 2, representing a partial rotation of the bottle portion about its vertical center axis from the front elevational view depicted in FIG. 2, said rear elevational view being opposite the front elevational view depicted in FIG. 2; and,

FIG. 5 is a fragmentary cross-section view taken along line 5—5 in FIG. 2.

The broken line environmental showing is for illustrative purposes only and does not form part of the claimed design.
